SHOWER CURTAIN HOLDER

Charles Minoff, Rockaway Park, N.Y., assignor to William L. Imershein and Charles Imershein, Valley Stream, N.Y.

Continuation-in-part of design application Ser. No. 13,281, Aug. 26, 1968. This application Sept. 19, 1969, Ser. No. 19,211

Term of patent 14 years

Int. Cl. D8—03; D9—99

U.S. Cl. D8—248

FIG. 1

FIG. 2

FIG. 3

FIG. 4

FIG. 5

FIG. 6

FIG. 1 is a perspective view of a shower curtain holder;

FIG. 2 is a medial cross section of the shower curtain holder of FIG. 1 installed around a shower curtain rod and through a grommet of a shower curtain;

FIG. 3 is an elevational view of the shower curtain holder from the side of the female portion of the snap holder;

FIG. 4 is an elevational view of the opposite side of the shower curtain holder;

FIG. 5 is a sectional view along the lines 5—5 of FIG. 1; and

FIG. 6 is a sectional view along the lines 6—6 of FIG. 1. The broken lines are for illustrative purposes only.

This application is a continuation-in-part of applicant's application Ser. No. D. 13,281, filed Aug. 26, 1968.

I claim:

The ornamental design for a shower curtain holder, substantially as shown and described.
